UNITED STATES PATENT OFFICE.

HENRY ALBERSWERTH, OF NEW HAVEN, MISSOURI, ASSIGNOR OF ONE-HALF TO HENRY ALBERSWERTH, JR., OF NEW HAVEN, MISSOURI.

THRESHING-MACHINE.

No. 837,909.

Specification of Letters Patent.

Patented Dec. 11, 1906.

Application filed December 28, 1905. Serial No. 293,674.

To all whom it may concern:

Be it known that I, HENRY ALBERSWERTH, a citizen of the United States, residing at New Haven, Missouri, have invented a certain new and useful Improvement in Threshing-Machines, of which the following is a full, clear, and exact description, such as will enable others skilled in the art to which it appertains to make and use the same, reference being had to the accompanying drawings, forming part of this specification, in which—

Figure 1 is a side elevation of a threshing-machine embodying the features of my invention. Fig. 2 is a longitudinal sectional view of the machine shown in Fig. 1. Fig. 3 is a transverse sectional view on the line 3 3 of Fig. 2. Fig. 4 is a transverse sectional view on the line 4 4 of Fig. 2, and Fig. 5 is a detail perspective view of one of the endless belts.

This invention relates to threshing-machines; and one object of the invention is to provide an improved mechanism for feeding the straw through the machine and beating it thoroughly to separate all the grain therefrom.

Another object of the invention is to provide means for distributing the straw uniformly upon each side of the medial line of the machine, so that all portions of the beating and feeding mechanism will be utilized.

Other advantages of my invention will hereinafter be pointed out.

Referring to the drawings, which represent the preferred form of my invention, 1 designates the frame or casing, comprising side walls and a top, and 2 designates the feed-chute at the front end of the machine. Mounted on a shaft 3 adjacent to the feed-chute is a threshing-cylinder 4, which first acts upon the sheaves of grain as they are introduced into the machine and separates most of the grain from the straw, the grain falling onto a tray 5, located under the threshing-cylinder. Said cylinder rotates in the direction of the arrow in Fig. 2 and feeds the straw over grate-bars 6 and into engagement with a winged beater 7, some of the grain and chaff falling through said grate onto the tray 5. A second grate 8, formed of a plurality of bars, is located under the winged beater, and the bars of said grate are farther apart than the bars of the grate 6. The winged beater is shown clearly in Fig. 4 and comprises a shaft 9, mounted in the sides of the frame and provided near its opposite ends with circular

plates 10. A spider 11 is secured to the shaft at approximately the center thereof, and wings comprising plates 12 are connected to said spider and to the end plates 10, said wing-plates being arranged at an angle to the shaft 9, which forms the axis of the winged beater. The wing-plates diverge in opposite directions from the central spider 11, as shown in Fig. 4, and the grate underneath said beater is provided with a plurality of ribs 13, which diverge in opposite directions from a central rib 14 in alignment with the spider on said shaft 9. The purpose of constructing the winged beater and the grate in this manner is to distribute the straw uniformly on both sides of the medial line of the machine, so that the entire surface of the beater and grate are utilized, and accordingly prevents the machine from becoming choked with a large mass of straw. The winged beater rotates in the direction of the arrow in Fig. 2 and carries the straw into engagement with a feeding-cylinder 15, provided with fingers 16, which beat the straw and feed it onto an endless belt, said feeding-cylinder carrying the straw over a semicircular grate 17, that is a continuation of the grate 8. Preferably a plate 18 is arranged above the winged beater, as shown in Fig. 2. The feeding-cylinder comprises a shaft 19, journaled in the sides of the frame and having secured thereto near its opposite ends circular end plates 20, in which a plurality of shafts 21 are rotatably mounted, said shafts extending parallel to the shaft 19.

Rigidly connected to each of the shafts 21 are a number of fingers 16, which normally extend radially from the cylinder through a cage that partially surrounds said cylinder and which consists of bars 22, that are connected at their opposite ends to cross-bars 24, extending the full width of the casing of the machine and secured to the side walls of the casing. If the fingers projected radially from the cylinder at all times, they would draw some of the straw through said cage after the straw had been carried over the semicircular grate 17, and to prevent this from occurring means is provided for withdrawing the fingers from the straw and moving them inwardly toward the axis of the cylinder after said fingers have passed over the semicircular grate, this being accomplished by the following mechanism:

Rigidly connected to one end of each shaft

is a block 25, having gear-teeth 26 and a head 27, provided with a surface which is concentric with a circular-shaped track 28, that is connected to one side of the casing, a 5 rack-bar 29 being also secured to the side of the casing in alinement with the track, as shown in Fig. 2.

In operation the circular face on the head of each block normally engages the track 28, 10 so that the fingers on the shaft to which said block is connected will be held in a radial position to beat the straw and feed it over the semicircular grate 17, any grain or chaff which remains in said straw falling through 15 the grate onto the tray 5. The rotative movement of the cylinder causes the end X of the head on said block to come into engagement with a stop or projection 30 on the rack-bar 29, whereby the shaft to which said block is connected 20 will be rocked in the reverse direction to that in which the cylinder is rotating and accordingly withdraw the finger from the straw and move it from its radial position. The continued rotative movement of the cylinder 25 causes the gear-teeth on said block to engage the teeth of the rack-bar 29, so that the shaft and fingers are rotated further in this direction until they have made approximately one-half of a revolution. When the circular face on the end y of the head of said block comes into engagement with the end w of the track 28, further rotative movement 30 is imparted to said shaft and its fingers until the fingers assume a radial position, in which 35 position they remain until after they have again passed the semicircular grate. As previously stated, the fingers of the cylinder feed the straw onto an endless belt 31, comprising bars 32, which are connected at 40 their opposite ends to lateral extensions on sprocket-chains 33, every third bar having an upwardly-projecting tooth 34, which teeth coöperate with each other to form pockets. In order that any grain which 45 remains in the straw will be shaken therefrom, the endless belt 31 is agitated intermittently, so that the grain will fall into the pockets formed by the teeth 34, this being effected by driving the sprocket-chains with eccentric 50 sprockets 35 and 36, as shown in Fig. 2, so that the entire belt will be intermittently raised and lowered, the movement of the belt ejecting the grain in the pockets onto a sieve at the inner end of the tray 5 and 55 the straw onto a rotating beater 37, which pitches it onto a second endless belt 38, similar in construction and operation to the belt 31, just described, the grain which accumulates in the pockets of said belt being ejected 60 onto a movable inclined table 39 and the straw being ejected through the discharge-opening 40 at the rear end of the machine, the table 39 being carried by links 41, connected to the sides of the frame.

65 From the foregoing description it will be

understood that the sheaves are fed into the chute 2 and are then acted upon by the threshing-cylinder, winged beater, feeding-cylinder, endless belts, and beater 37, which cause the grain to be separated from the straw and fall onto the tray 5 and sieve and also on the inclined table 39. At the inner end of the tray 5 is a coarse sieve 42, previously referred to, and below this sieve is a second sieve 43, of finer mesh, so that the 70 heavy tailings, pieces of straw, &c., will remain on the sieve 42 and the grain and light chaff will sift through onto the sieve 43, the grain passing through this sieve onto the inclined floor 44 of a movable box-like receptacle 45 and then into a spiral conveyer 45', which carries the grain into a suitable receptacle placed at the side of the machine and at the end of the conveyer.

As shown in Fig. 2, the tray 5 inclines 85 downwardly toward the rear end of the machine and is supported by links 46, connected to the tray and to the sides of the frame of the machine, said tray being agitated to cause the grain and chaff thereon to travel to 90 the sieve 42 at the inner or lower end of the tray. Deflector-plates 47 are connected to the sides of the frame above the side bars 48 of the tray, so that none of the grain will be wasted. The box-like receptacle which carries the sieve is provided with spaced lugs 49, which support the sieve 43, and thus enables its position relatively to the one above it to be changed. This receptacle is also adapted to be agitated and is carried by links 50, 95 which are pivoted to the sides of the frame. The tray 5 and receptacle 45 are agitated by means of eccentrics 51 on a shaft 52, through eccentric-rods 53, connected, respectively, to the tray and to the receptacle, the inclined 100 table 39 being connected to the receptacle 45 by a link 54, so that it moves with it.

A fan 55, mounted in a casing 56, having deflectors 57, operates to blow any straw, chaff, or other substance which rests on the 110 sieves through the discharge-opening 40, and any heavy tailings will fall through the opening 58 in the end of the box-like receptacle into a spiral conveyer 59, that carries them out of the machine, so that they may be 115 worked over, if desired. Fastened to the upper edge of the casing 56 and to the end of the tray 5 is a piece of flexible material 56', which prevents the blast of air from escaping beneath said tray.

For driving the mechanism above described the shaft 3 of the threshing-cylinder is provided with a pulley (not shown) which receives a belt that is driven from some source of power, and the opposite end of 125 said shaft is provided with a pulley 60, which drives a belt 61, that passes over wheels 62 and 63 on the shaft 9 and the eccentric-shaft 52. The eccentric-shaft carries a sprocket-wheel 64 (shown in dotted lines in Fig. 1,) 130

which drives a chain 65, that passes over a large sprocket-wheel 66 on the end of the shaft 19 of the feeding-cylinder, said chain also passing over a sprocket-wheel 67 on the 5 shaft carrying the sprocket-wheel 35, which drives the endless belt 31, and over an idler 68. The shaft which carries the sprocket 36, that aids in driving the endless belt 31, is provided with a sprocket 69, which drives a 10 chain 70, that passes over sprockets 71 and 72 on the shafts of the beater 37 and the drive-sprocket for the endless belt 38. The means for driving the fan and spiral conveyors is not shown, but may be of any suitable 15 construction.

Having thus described my invention, what I claim as new, and desire to secure by Letters Patent, is—

1. In a threshing-machine, a grate, a feeding-cylinder mounted above said grate and provided with fingers which normally project radially therefrom for engaging a mass of straw and moving it over said grate, and means for moving said fingers out of their radial position and within the periphery of the cylinder after they have passed said grate; substantially as described.
2. In a threshing-machine of the class described, a grate, a device located above said 20 grate and provided with fingers which normally project outwardly for engaging a mass of material and moving it over said grate, and means for moving said fingers within the 25 periphery of the cylinder after they have passed said grate; substantially as described.
3. In a threshing-machine, a semi circular grate, a cylinder located above said grate and provided with fingers which normally project radially therefrom to engage a mass 30 of straw and move it over said grate, a cage partially surrounding said cylinder and constructed to permit the fingers of the cylinder to project therethrough, and means for moving said fingers out of their radial position 35 after they have passed the grate to withdraw said fingers from the straw and thereafter moving said fingers through the interior of the cylinder and into a radial position before they reach the position for engaging the 40 straw; substantially as described.

4. In a threshing-machine, a grate, a feeding-cylinder comprising a plurality of rotatably-mounted shafts having fingers which normally project radially from the cylinder 45 to engage straw and move it over the grate, blocks carried by said shafts, and means cooperating with said blocks for turning the shafts in a direction reverse to that in which the cylinder is rotating to withdraw the fingers from the straw after they have passed 50 the grate and thereafter move said fingers into a radial position; substantially as described.
5. In a threshing-machine, a grate, a feed-

ing-cylinder mounted above said grate and 65 comprising a plurality of rotatably-mounted shafts provided with fingers which normally extend radially for engaging straw and moving it over said grate, a cage partially surrounding said cylinder and constructed to 70 permit said fingers to project therethrough, a block secured to each shaft and provided with gear-teeth and with a head, a stationary rack-bar provided with means that is engaged by the head on the block during the rotation of the cylinder whereby the shaft is turned to move said fingers out of a radial position, the teeth on said rack-bar and said head thereafter engaging to further rotate 75 said shaft in a direction reverse to that in 80 which the cylinder is rotating, and a stationary track for engaging the head of the block to still further rotate the shaft and cause the fingers to assume a radial position; substantially as described.

6. In a threshing-machine, an approximately semicircular grate, a cylinder located above said grate and provided with fingers which project therefrom to engage straw and move it over said grate, a cage partially surrounding said cylinder and comprising bars spaced apart and connected at their opposite ends to stationary cross-bars and means for turning said fingers through an arc of approximately one hundred and eighty degrees 90 to withdraw them from the straw and again move them into a radial position; substantially as described.

7. In a threshing-machine, a casing, a threshing-cylinder mounted in said casing, 100 mechanism for feeding the straw through said casing comprising an endless belt provided with pockets, means for agitating said belt to cause any grain in the straw to drop into said pockets, and a feeding-cylinder arranged between the threshing-cylinder and the endless belt; substantially as described.

8. In a threshing-machine, a casing, a threshing-cylinder mounted in said casing, 110 mechanism for feeding the straw through said casing comprising an endless belt provided with pockets, a sprocket-chain forming a part of said belt, eccentric sprocket-wheels for driving said chain whereby the belt is raised and lowered intermittently to agitate 115 the straw and cause any grain therein to drop into said pockets, and a feeding-cylinder arranged between the threshing-cylinder and the endless belt; substantially as described.

In testimony whereof I hereunto affix my signature, in the presence of two witnesses, this 22d day of December, 1905.

HENRY ALBERSWERTH.
